UNITED STATES PATENT OFFICE.

LOREN B. SPAULDING, OF PERKINSVILLE, VERMONT.

STANCHION.

1,110,514.

Specification of Letters Patent. Patented Sept. 15, 1914.

Application filed April 7, 1913. Serial No. 759,503.

To all whom it may concern:

Be it known that I, LOREN B. SPAULDING, a citizen of the United States, residing at Perkinsville, in the county of Windsor and

5 State of Vermont, have invented a new and useful Stanchion, of which the following is a specification.

One object of the present invention is to provide novel means for limiting the pivotal 10 movement of the frame of the stanchion when the fetter is in open position.

With the foregoing and other objects in view which will appear as the description proceeds, the invention resides in the combination and arrangement of parts and in the details of construction hereinafter described and claimed, it being understood that changes in the precise embodiment of invention can be made within the scope of 20 what is claimed without departing from the spirit of the invention.

In the drawing:—Figure 1 shows the invention in elevation, the fetter being in open position; Fig. 2 is a transverse section on 25 the line 2—2 of Fig. 1; Fig. 3 is a transverse section on the line 3—3 of Fig. 1; Fig. 4 is a transverse section on the line 4—4 of Fig. 1; Fig. 5 is a fragmental elevation, the view point in Fig. 5 being 90° remote from the 30 view point in Fig. 1; and Fig. 6 is a fragmental perspective of the upper portion of the pivoted frame of the stanchion.

In the drawing, there is shown a fixed lower support 1 and a fixed upper support 2, the same, ordinarily, being timbers which extend transversely of the stalls adjacent the feed boxes. The invention includes a frame denoted generally by the numeral 3, the frame comprising an upright 4 and trans- 40 verse arms 5 and 6 secured to the ends of the upright 4.

The upper arm 5 is a composite structure and includes a back plate 7, one end of which is secured to the upright 4, there 45 being a butt block 8 secured to the back plate 7 in the angle defined by the back plate 7 and the upright 4, as seen most clearly in Fig. 6. The outer end of the butt block 8 constitutes a shoulder 9, having functions which will be set forth hereinafter. Secured to the butt block or to any other accessible portion of the upper arm 5 is a 50 staple-shaped guide 10. In the block 8 or in any other portion of the upper arm 5 is an opening 15, adapted to receive a shaft 16, the upper end of which is mounted in

the fixed upper support 2. If desired, a washer 17 may be interposed between the upper support 2 and the upper arm 5 of the frame 3.

The lower arm 6 of the frame 3 comprises a back plate 18 and a front plate 19, the ends of which are secured to the lower end of the upright 4. Interposed between the plates 18 and 19 and engaged with the upright 4 is a butt block 20 in which is journaled the upper end of a shaft 21, the lower end of which is secured to or otherwise mounted in the fixed lower support 1. If desired, another washer 17 may be interposed between the lower arm 6 of the frame 3 and the fixed lower support 1.

Through the spaced members 18 and 19 is inserted a pivot element 22, constituting a support for the lower end of a fetter 23. The fetter 23 may stand in an open position, as shown in Fig. 1, or it may be swung into closed position, into abutment with the shoulder 9. A latch 24 is pivoted as indicated at 25 to the upper end of the fetter 23, 75 the latch being mounted to slide in the guide 10. In the lower edge of the latch 24 there is a notch 27, adapted to coöperate with the guide 10, to hold the fetter 23 in closed position.

Fixed to and upstanding from the lower support 1, or otherwise held against movement, are spaced projections 28. Secured to the outer edge of the fetter 23 is an outwardly extended tongue 29, an attaching element 30 being passed through the upper end of the tongue 29 into engagement with the fetter 23. The lower end of the tongue 29 terminates in a reduced tip 31. As indicated at 32, the spaced members 18 and 19 of the frame 3 are extended beyond the fetter 23 and the lower edges of the members 18 and 19 are beveled off as indicated at 33.

When the fetter stands in open position, as shown in Fig. 1, the lower end of the tongue 29 will be swung inwardly, so that the tip 31 of the tongue lies between the projections 28. Therefore, when the fetter 23 is in open position, the frame 3 can have but a very limited movement upon the shafts 16 and 21. When, however, the fetter 23 is swung into a closed position, the frame 3 may be swung freely, upon the shafts 16 and 21, because, during the pivotal movement of the fetter 23 to a closed position, the tip 31 of the tongue 29 is swung outwardly so that it no longer lies between the projec- 105 110

tions 28. Owing to the fact that the lower edges of the members 18 and 19 are beveled as indicated at 33, the frame 3 may swing independently of the projections 28 when the fetter 23 is in closed position. It is to be observed that when the fetter 23 is swung into an open position, the tongue 29 retires between the extensions 32 of the members 18 and 19. Consequently, the tongue 29 is held securely against swinging movement upon the element 30, the tongue further, being reinforced by the extensions 32, so as to withstand the strain incident to the engagement between the tip 31 and one of the projections 28.

When it is desired to swing the fetter 23 into an open position, the frame 3 may be tilted so that it no longer stands in vertical alignment with the supports 1 and 2. It is thus possible to locate the frames 3 in relatively close relation to each other, so that a single operator may reach over an animal and loosen the fetter 23 which restrains another adjacent animal, it being unnecessary to stand adjacent each animal, in order that the same may be set free. The construction of the device is such that the restrained animal cannot pass forwardly and stand with its feet in the feed box, a contingency tending to cause the fecal matter to be deposited upon the floor of the stall, instead of in the

drainage trough. The ends of the frame 3 lie close to the supports 1 and 2, and, although a free pivotal movement of the frame is provided, the supporting shafts 21 and 16 cannot readily become bent or broken.

Having thus described the invention, what is claimed is:

In a stanchion, a pivotally mounted frame including spaced members; a fetter pivoted between the spaced members for movement into open and closed positions with respect to the frame; a tongue applied to the fetter; a securing element connecting the tongue with the fetter; a support and fixed projections on the support with which projections the tongue engages when the fetter is in an open position, the tongue retiring between the spaced members when the fetter is in an open position, whereby the spaced members will act as lateral braces for the tongue and prevent a movement of the tongue on the securing element.

In testimony that I claim the foregoing as my own, I have hereto affixed my signature in the presence of two witnesses.

LOREN B. SPAULDING.
